UNITED STATES PATENT OFFICE.

LUCIAN E. PARKER, OF WADSWORTH, OHIO, ASSIGNOR TO THE OHIO MATCH COMPANY, OF WADSWORTH, OHIO, A CORPORATION OF OHIO.

SLIDE FEEDER FOR MATCH MACHINES.

Application filed January 16, 1925. Serial No. 2,969.

This case is a continuation in part of my application of the same title filed May 29, 1924, Serial No. 716,677.

The object of this invention is to provide a device for automatically arranging a plurality of match-box slides in regular uniform order, easily and expeditiously, so that they may thereafter be fed into the slide positioning mechanism of a match boxing machine without additional arrangement or manipulation.

By the employment of my device the arrangement of the slides is so materially expedited that stopping of the boxing machine for lack of properly arranged slides, as is sometimes the case when the slides are arranged by hand, is eliminated.

Moreover, my machine will do the work of a number of operatives, and requires the service of only one attendant for its efficient operation, and thus, in addition to increasing production, dispenses with the services of a number of employees, and releases such employees for other duties.

The invention consists in a slide feeder for match machines, comprising a feeder trough arranged at an incline and adapted to receive slides in haphazard arrangement, this trough being provided with a plurality of similar paths into which the slides may fall in predetermined position, and down which they may travel by gravity due to the inclination of the trough, means for agitating the slides fed to the trough for the purpose of causing them to assume the desired predetermined position in the paths, means for positively arresting the travel of the slides in uniform series and for similarly positively discharging them, combined with means for receiving the discharged slides and for conveying them to a boxing machine in order, as discharged from the feeder, as I will proceed now to explain and finally claim.

In the accompanying drawings illustrating the invention, in the several figures of which like parts are similarly designated, Figure 1 is a side elevation of a device embodying my invention, a portion of one side of the trough being broken away to show parts of the mechanism lying behind it. Fig. 2 is a plan view of the feeder trough and associated mechanism, a portion thereof being broken out. Fig. 3 is an enlarged sectional detail of the discharge end of the

trough, showing the slide arresting and discharging mechanism. Figs. 4 and 5 are, respectively, a plan of the conveyor mechanism, and a side elevation of same, portions thereof being broken away. Fig. 6 is an enlarged transverse section taken in the plane of line 6—6, Fig. 5.

The feeder trough has a bottom 1, similar sides 2, and an end 3 sloping toward the bottom 1, and this trough is arranged at an incline, and may be supported upon suitable framework 4.

Arranged upon the bottom of the trough is a plurality of similar guide members 5 suitably uniformly spaced apart to provide a plurality of similar paths 6 of such width as to loosely accommodate match-box slides when such slides fall into same upon their sides or ends, but incapable of receiving the slides in any other positions.

Arranged transversely of the trough, adjacent to its ends, are shafts 7 and 8 respectively, carried in suitable similar bearings 9, and upon these shafts are mounted, adjacent to the sides 2 of the trough, sprockets 10 and 11 respectively. These sprockets carry chains 12 provided at suitable intervals with enlarged links 13 between which are supported agitator rods 14 which extend transversely across the trough. As the sprockets are rotated, as by means of a chain and sprocket connection indicated at 15, the chains will travel in the direction indicated by the arrows (Fig. 1) and will drag the rods 14 up the trough in proximity to the tops of the guide members 5.

Mounted in suitable bearings 16 and 17 supported at the sides of the trough and adjacent to the lower or discharge ends of the paths 6 are shafts 18 and 19 which carry pluralities of similar friction or cam members 20 and 21 respectively. These cam members are so arranged upon their shafts as to lie in pairs centrally above and below the discharge ends of the paths, and act to frictionally engage and arrest the slides as they descend the paths and to frictionally and positively discharge the slides, in a manner as will be hereinafter explained. The shaft 18 is provided with a lever 22 fixed to it and connected by a link 23 with an extension 24 of a lever arm 25 fixed to the shaft 19 and carrying a suitable treadle 26. The lever 25 and with it the shafts 18 and 19 and their respective cam members

20 and 21 are held in normal position for arresting movement of the slides down the paths, as indicated in Fig. 3, by means of a suitable spring or other resilient connection 27.

The bottom 1 of the trough is extended beyond the discharge ends of the paths as indicated at 28 and is provided with an angle member 29 against which the slides discharged from the paths are stopped, and which maintains the thus discharged slides in uniform alignment.

Baffle plates A and B pivotally supported at a' a' and b' b' in the sides 2 of the trough and resting upon the upper and lower flights respectively of the chains 12, are provided for a purpose hereinafter appearing.

At one side of the lower end of the feeder trough, herein indicated as the right hand side, the extension 28 is laterally elongated, and connected to it in any suitable manner is a conveyor for carrying off the uniformly arranged slides discharged from the feeder (Figs. 4, 5 and 6). This conveyor comprises a pair of belts 30 travelling in parallel relation to each other, as particularly shown in Fig. 4, and carried by similar pulleys 31 and 32 arranged at a suitable distance from each other. The pulleys 31 are supported in bearings 33 made adjustable, for the purpose of adjusting the tension upon the belts 30, by means of slot and bolt connections, or the like, indicated at 34. The pulleys 32 furnish the drive for the belts 33, one of these pulleys being driven by means of a suitable drive pulley 35 mounted upon its shaft and the power therefrom being transmitted to the other pulley 32 through gears 36 of the same pitch-diameter. It will thus be seen that by means of this gearing, the two pulleys 32 are driven at the same speed, and that, consequently, the two belts 30 have the same linear speed, so that any two points lying directly opposite each other upon the two belts will travel from one end of the conveyor to the other in the same relationship.

The conveyor is provided with a belt guiding framework composed of longitudinal stringers 37 to which are attached at suitable intervals angle members 38 which carry guides 39 against which the belts 30 ride, and adjustably supported upon the angle members 38 of one side of the conveyor by means of slot and bolt connections 40 (Fig. 5) are angle members 41 extending laterally over the top of the conveyor and carrying a guard rail 42 arranged centrally over the path between the belts.

Arranged at the discharge end of the conveyor is a chute 43 comprising a bottom 44, sides 45 and a top rail 46, into which the slides are discharged from the belts 30 and down which they slide and stack without losing their desired uniform arrangement,

and through which they are introduced to the positioning mechanism of the match boxing machine.

As one appropriate means of supplying slides to the feeder trough as desired, I may provide a hopper 47 (Fig. 1) having a bottom composed of a plurality of similar belts 48 carried by pulleys 49 and 50 arranged upon shafts 51 and 52, respectively, at opposite ends of the hopper, and the shaft 51 having a hand wheel 53 with spokes or hand grips 54, by which the shaft 51 may be turned to impart motion to the belts 48 in the direction of the arrow, Fig. 1, whereby slides deposited in a mass in the hopper 47 may be discharged therefrom at will, in desired quantities, into the feeder trough.

The operation of the device is as follows:—As above indicated, slides deposited in a mass in the hopper 47 may be discharged in suitable quantities into the upper end of the feeder trough by imparting appropriate travel to the belts 48. Some of these slides will immediately drop into the paths formed by the guides 5 in position upon their sides and will slide down the paths until arrested by the cam members 20 and 21 in the position indicated at a , Fig. 3. Those slides which do not thus fall into the paths, but which ride upon the tops of the guide members 5 will slide down these guide members and come in contact with the travelling agitator bars 14, which will carry them along the tops of the guide members toward the upper end of the trough until they drop into the paths either upon their sides or their ends. If a large number of slides is fed into the trough, these slides will tumble down the trough until arrested by the lower or ascending flight of agitator bars 14, by which they will be carried up the trough, and during this upward travel will be so shifted about as to assume positions which will permit them to fall between the guide members 5 and into the paths. Obviously, slides in the trough which do not fall into the paths will be carried up the incline of the trough by the agitator bars 14 as many times as is necessary to cause them to fall into the paths.

Those slides which fall into the paths upon their ends, will be turned upon their sides by contact with them of the ascending agitator bars 14, for the reason that these bars are in such proximity to the tops of the guide members 5 as to clear slides resting in the paths upon their sides, but to intercept and turn over slides resting therein upon their ends.

If more slides are fed to the feeder trough than can be conveniently handled by the ascending rods 14 and have, therefore, a tendency to spill past the line of the shaft 7 they will be arrested by the baffles A and B so as to be further acted upon by the rods 14.

As the slides assume the proper position upon their sides, they will travel down the paths until arrested by the cam members 20 and 21, as above pointed out, and will back 5 up one behind another in the paths in uniform series.

When it is desired to discharge a series of slides from the paths, the attendant of the machine presses her foot upon the treadle 26 and thus, by means of the link and lever 10 connection of the shafts 18 and 19, turns these shafts in opposite directions and causes the cam members 20 and 21 by frictional engagement with the sides of the slides to 15 positively simultaneously discharge one slide from each of the paths. It will be seen that, due to the conformation of the slide engaging faces of the cams 20 and 21, as soon as the slide has been pushed forward, it will be 20 freed by the cams and will slide to a position abutting against the angle member 29 as indicated by the dotted lines *b*, Fig. 1. Of course, as soon as the series of slides is discharged from the paths, the operator will 25 release the treadle 26 and the spring 27 will return it and the shafts and cams to their normal position, as indicated in Fig. 3, and the cams will frictionally engage and push back the succeeding series of slides, thereby 30 moving back all of the following slides in their respective paths a distance sufficient to preclude the possibility of their interfering with the clearing of the previously released series of slides from the extension 28.

It will be noted that all of the slides discharged against the angle member 29 are in uniform relative arrangement, and they may be swept from the extension 28 by the operator placing her hand behind the slide the 35 farthest to the left and pushing that slide and with it those ahead of it into engagement with the parallel travelling belts of the conveyor mechanism of Figs. 4, 5 and 6. These belts pick up the slides one at a time, by frictional engagement with their ends, and support and convey them to, and release them at, the entrance of the chute 43 into which they drop in regular order and arrangement, and in which they stack up in 40 such arrangement for subsequent introduction into the positioning mechanism of the boxing machine.

If, by chance, any slides should become mutilated in their passage through the slide 45 feeder, they may be picked out and discarded when discharged from the paths 6 of the feeder, or if not noticed at that time and discovered after having been picked up by the belts 30, they may be pushed from between the belts and will drop down between the stringers 37.

It will thus be seen that I provide a simple, efficient and automatic device for arranging match-box slides in regular predetermined order and for conveying the thus

arranged slides, without disarrangement, to a match boxing machine. Moreover, it will be apparent that no hand manipulation of the slides is necessary other than that required to sweep them from the extension 28 70 into engagement with the conveyor mechanism.

Various changes in construction and arrangement of parts is contemplated as within the spirit of the invention and the scope 75 of the following claims.

What I claim is:—

1. In a slide feeder for match machines, a feeder trough adapted to receive slides in haphazard arrangement, means in said trough defining a plurality of paths adapted to receive said slides in predetermined position and through which said slides travel, and means comprising friction members arranged in pairs adjacent to the discharge 80 ends of said paths and adapted by their combined engagement with the slides to arrest travel of the slides in the paths, said means arranged for actuation to positively eject a single slide from the discharge end of each 85 of said paths.

2. In a slide feeder for match machines, a feeder trough adapted to receive slides in haphazard arrangement, means in said trough defining a plurality of paths adapted to receive said slides in predetermined position and in which said slides travel, and means adjacent to the discharge ends of said paths arranged to frictionally engage said 90 slides and arrest their travel, said slide arresting means capable of actuation to positively discharge said slides from said paths in uniform series.

3. In a slide feeder for match machines, a feeder trough adapted to receive slides in haphazard arrangement, means in said trough defining a plurality of paths adapted to receive said slides in predetermined position and in which said slides travel, and means adjacent to the discharge ends of said paths arranged to frictionally engage said 105 slides and arrest their travel, said slide arresting means capable of actuation to move said slides to and positively discharge them 110 from said paths in uniform series and said means upon their return movement operating to push back slides travelling behind those discharged.

4. In a slide feeder for match machines, a feeder trough adapted to receive slides in haphazard arrangement, means in said trough defining a plurality of similar paths adapted to receive said slides in predetermined position and in which said slides travel by gravity, means comprising pairs 120 of cam members arranged adjacent to the discharge ends of said paths for arresting the travel of said slides in uniform series by frictional engagement therewith, and means 125 for imparting movement to said cams 130

- whereby they may positively eject slides from said paths in uniform series.
5. In a slide feeder for match machines, a feeder trough adapted to receive slides in haphazard arrangement, means in said trough defining a plurality of similar paths adapted to receive said slides in predetermined position and in which said slides travel by gravity, means comprising pairs of cam members arranged adjacent to the discharge ends of said paths for arresting the travel of said slides in uniform series by frictional engagement therewith, and means for imparting movement to said cams whereby they may discharge slides from said paths in uniform series and said cams upon their return movement operating to push back slides travelling behind those released.
- 20 6. In a slide feeder for match machines, an inclined feeder trough adapted to receive slides in haphazard arrangement, a plurality of similar guide members arranged in said trough and uniformly spaced apart to form paths adapted to receive the slides in predetermined position and in which said slides travel by gravity, means comprising pairs of similar cam members located adjacent to the discharge ends of said paths and adapted to arrest the travel of said slides by frictional engagement therewith, and means for simultaneously imparting movement to said cam members to positively eject said slides from said paths in successive uniform series.
- 35 7. In a slide feeder for match machines, an inclined feeder trough adapted to receive slides in haphazard arrangement, a plurality of similar longitudinal guide members uniformly spaced apart in said trough to form paths to receive said slides in predetermined position and in which said slides travel by gravity, means comprising a pair of similar cam members arranged adjacent to the discharge ends of said paths and adapted to arrest the travel of said slides by frictional engagement therewith above and below them, and means for simultaneously imparting motion to all of said pairs of cam members to positively successively discharge said slides from said paths in uniform series.
- 40 8. In a slide feeder for match machines, an inclined feeder trough adapted to receive slides in haphazard arrangement, a plurality of similar guide members arranged longitudinally of said trough and uniformly spaced apart to form a plurality of similar paths to receive said slides in predetermined position and in which paths said slides travel by gravity, shafts arranged above and below said guide members adjacent to the discharge ends of said paths, a plurality of cam members on each shaft equal in number to the number of said paths and so arranged upon said shafts as to form a pair of cams

for each path and adapted to arrest the travel of the slides in said paths by frictional engagement therewith, and means for simultaneously oscillating said shafts in opposite directions for the purpose of positively ejecting the slides from said paths in uniform series.

5 9. In a slide feeder for match machines, an inclined trough adapted to receive slides in haphazard arrangement, means defining a plurality of paths longitudinally of said trough and adapted to receive slides in predetermined position only, and means including a rod extending transversely of said trough and travelling longitudinally thereof entirely above said path-defining means for ensuring the positioning of the slides in said paths in the desired position.

10. In a slide feeder for match machines, an inclined feeder trough adapted to receive slides in haphazard arrangement, means defining a plurality of paths extending longitudinally of said trough and adapted to receive slides in predetermined position only, and means including a rod arranged transversely of said trough and travelling longitudinally therethrough entirely above said path defining means and adapted to agitate the slides fed to said trough and to ensure the desired positioning of the slides in said paths.

11. In a slide feeder for match machines, an inclined feeder trough adapted to receive slides in haphazard arrangement, a plurality of similar guide members arranged longitudinally of said trough and forming between them paths to receive said slides in one of two predetermined positions, said slides adapted to travel by gravity longitudinally of said paths, and means including a rod arranged transversely of said trough and travelling longitudinally therethrough entirely above said guides in a direction opposite to the direction of travel of said slides for agitating said slides and ensuring the positioning of same in said paths as desired.

12. In a slide feeder for match machines, an inclined feeder trough adapted to receive slides in haphazard arrangement, a plurality of similar guide members arranged longitudinally of said trough and spaced apart to form a plurality of paths adapted to receive said slides upon their sides or ends and in which said slides travel by gravity, and means including a plurality of rods arranged transversely of said trough and travelling longitudinally entirely above said guides and adapted to cause all slides deposited in said paths upon their ends to be turned upon their sides as desired.

13. In a slide feeder for match machines, an inclined feeder trough adapted to receive slides in haphazard arrangement, a plurality of similar guide members arranged lon-

itudinally of said trough and spaced apart to form a plurality of similar paths adapted to receive said slides in position upon their sides or ends and not otherwise and in which 5 said slides travel, and a travelling agitator including a plurality of rods arranged transversely of said trough and moving longitudinally thereof above said guide members in a direction opposite to the direction of 10 the travel of said slides and adapted to agitate said slides and cause same to fall into said paths as desired and to cause slides which have fallen into said paths upon their ends to be turned upon their sides.

15. 14. In a slide feeder for match machines, an inclined feeder trough adapted to receive slides in haphazard arrangement, a plurality of similar guide members arranged longitudinally of said trough and spaced apart 20 to form a plurality of uniform longitudinal paths adapted to receive slides in predetermined position, a pair of shafts arranged transversely of said trough adjacent to its ends and carrying similar sprockets adjacent to their ends, a pair of chains carried by said sprockets, and agitator members carried by said chains and extending transversely of said trough and adapted upon rotation of said shafts to travel longitudinally 25 of said trough entirely above said guide members for the purpose of agitating said slides and causing same to fall into said paths in the desired predetermined position.

15. 15. In a slide feeder for match machines, an inclined feeder trough adapted to receive slides in haphazard arrangement, a plurality of similar guide members arranged longitudinally of said trough and spaced apart 30 to form a plurality of similar paths extending longitudinally of said trough and adapted to receive said slides in predetermined position and in which said slides travel by gravity, a travelling agitator for agitating said slides and causing same to fall into 35 said paths in the desired position, means adjacent to the discharge ends of said paths for frictionally engaging said slides and arresting their travel, means for actuating said slide-arresting means for the purpose of 40 discharging slides from said paths in uniform series, means for receiving the thus discharged slides and maintaining them in uniform arrangement, and a conveyor mechanism cooperating with the slide receiving 45 means and comprising a pair of parallel travelling belts of equal linear velocity for conveying said slides and a chute for receiving said slides from said belts and for conveying them in uniform stacked relation to 50 a boxing machine.

16. 16. In a slide feeder for match machines, an inclined feeder trough adapted to receive slides in haphazard arrangement, a plurality of similar guide members arranged longitudinally of said trough and spaced apart 55 to form a plurality of similar paths extending longitudinally of said trough and adapted to receive said slides in predetermined position and in which said slides travel by

gravity, a travelling agitator for agitating said slides and causing same to fall into said paths in the desired position, means adjacent to the discharge ends of said paths for frictionally engaging said slides and arresting their travel, means for actuating said slide-arresting means for the purpose of discharging slides from said paths in uniform series, means for receiving the thus discharged slides and maintaining them in uniform arrangement, and a conveyor mechanism cooperating with the slide receiving means and comprising a pair of travelling belts for conveying said slides to a boxing machine. 70

17. 17. In a slide feeder for match machines, an inclined feeder trough adapted to receive slides in haphazard arrangement, a plurality of similar guide members arranged longitudinally of said trough and spaced apart 75 to form a plurality of similar paths extending longitudinally of said trough and adapted to receive said slides in predetermined position and in which said slides travel by gravity, a travelling agitator for agitating said slides and causing same to fall into said paths in the desired position, means adjacent to the discharge ends of said paths for frictionally engaging said slides and arresting their travel, means for actuating said slide-arresting means for the purpose of discharging slides from said paths in uniform series, means for receiving the thus discharged slides and maintaining them in uniform arrangement, and a conveyor mechanism 80 cooperating with the slide receiving means and comprising a pair of parallel travelling belts of equal linear velocity for conveying said slides and a chute for receiving said slides from said belts and for conveying them in uniform stacked relation to a boxing machine. 85

18. 18. In a slide feeder for match machines, an inclined trough adapted to receive slides in haphazard arrangement, means defining a plurality of paths longitudinally of said trough and adapted to receive slides in predetermined position, means extending transversely of said trough and travelling over said path-defining means for ensuring the 90 positioning of the slides in said paths in the desired position, and means fixed with relation to said travelling means for arresting the movement of slides not received in said paths. 95

19. 19. In a slide feeder for match machines, an inclined trough adapted to receive slides in haphazard arrangement, means defining a plurality of paths longitudinally of said trough and adapted to receive slides in predetermined position, means extending transversely of said trough and travelling over said path-defining means for ensuring the 100 positioning of the slides in said paths in the desired position, and means comprising 105

a baffle fixed with relation to said travelling means for arresting the movement of slides not received in said paths.

20. In a slide feeder for match machines, an inclined trough adapted to receive slides in haphazard arrangement, means defining a plurality of paths longitudinally of said trough and adapted to receive slides in predetermined position, means including continuous travelling chains and rods carried thereby moving over said path-defining means for ensuring the positioning of the slides in said paths in the desired position, and means comprising baffles pivotally supported transversely of said trough and having their free ends resting upon the upper and lower flights respectively of said chains for arresting the movement of slides not received in said paths.
21. In a slide feeder for match machines, an inclined trough adapted to receive slides in haphazard arrangement, means defining a plurality of paths longitudinally of said trough and adapted to receive slides in predetermined position, means travelling over said path-defining means for ensuring the positioning of the slides in said paths in the desired position, and means comprising

a baffle pivotally supported transversely of said trough and having its free edge engaging the longitudinally travelling means for arresting the movement of slides not received in said paths.

22. In a slide feeder for match machines, an inclined trough adapted to receive slides in haphazard arrangement, means defining a plurality of paths longitudinally of said trough and adapted to receive slides in predetermined position, means including endless travelling chains carrying rods moving over said path-defining means for ensuring the positioning of the slides in said paths in the desired position, and means comprising a pair of baffles extending transversely of said trough, one of said baffles having its edge riding upon the upper flight of said chains and the other baffle having its edge riding upon the lower flight of said chains and said baffles cooperating to close said trough transversely above said path-defining means for arresting the movement of slides not received in said paths.

In testimony whereof I have hereunto set my hand this 13th day of Jan'y A. D., 1925.

LUCIAN E. PARKER.
